UNITED STATES PATENT OFFICE.

THEODOR O. L. SCHRADER, OF NEW YORK, N. Y.

PENCIL.

SPECIFICATION forming part of Letters Patent No. 372,710, dated November 8, 1887.

Application filed May 10, 1887. Serial No. 237,681. (No model.)

To all whom it may concern:

Be it known that I, THEODOR O. L. SCHRADER, of the city, county, and State of New York, have invented a new and Improved 5 Pencil, of which the following is a full, clear, and exact description.

My invention relates to that class of pencils which carry loose leads, and more particularly to that style of pencil which automatically 10 limits the extent to which the lead can project from the holder.

The invention consists in novel means for holding the lead to prevent its dropping too far out; also in novel means for operating the 15 clamping-jaws, and in details of construction and combination of parts, as will be more fully hereinafter set forth.

Reference is to be had to the accompanying drawings, forming part of this specification, 20 in which--

Figure 1 is a central longitudinal section of my improved pencil without the hammer. Fig. 2 is a partly-broken side view of the same. Fig. 3 is a side view of the lower end of the 25 lead-containing tube in my pencil. Fig. 4 is a longitudinal sectional view of same, taken on line *c c*, Fig. 5. Fig. 5 is a cross-section on line *kk*, Fig. 4. Fig. 6 is a perspective view of the lead-gripper. Fig. 7 is a side view, 30 partly in central longitudinal section, of a modification of the pencil. Fig. 8 is a central longitudinal view of a pencil having all my improvements. Fig. 9 is a side view of the upper end of the lead-carrying tube to be used 35 in connection with the pencil shown in Fig. 8.

A in the drawings represents the lead-carrying tube, and *B* a lead within same. Part of the tube *A* is surrounded by a sheath or casting, *D*. The lower part of the tube *A*, where 40 it projects from the sheath *D*, and the lower part of sheath *D* are covered by a tube, *E*, which is contracted a short distance below the end of the sheath *D* and forms the shoulder *a*. The tube *E* is securely fastened to the 45 sheath *D*, and is slit, as at *b*, longitudinally below the shoulder *a*, its lower end forming the gripping-jaws *F*. Each slit *b* has the two enlargements *d* and *e*. (Best seen in Fig. 2.) A spiral spring, *f*, or equivalent rubber cushion, surrounds the tube *A* within the tube *E* 50 and above the shoulder *a*. At its upper end

it presses against the shoulder *g* on tube *A*, which shoulder *g* can abut against the lower end of sheath *D*, Fig. 1. The lower end of the tube *A* carries a perforated ring, *h*, through 55 the holes of which extend the jaws *F* on the tube *E*. The enlargements *e* of slits *b* are to receive the bridges or solid parts *i* of the perforated ring *h*. By pressing down on tube *A* the inner thickness of the ring *h* will enter 60 between the jaws *F* and force them apart to allow the lead *B* to pass down. When this pressure is released, the spring *f*, pressing against shoulder *a* and shoulder *g*, will force the tube *A* upward, which causes the outer thickness of the ring *h* to crowd against the outer side of the jaws *F*, which movement closes said 65 jaws upon the lead *B* and holds them in the closing position.

To insure that the lead *B* when released by 70 the downward pressure on tube *A* and by the opening of the jaws *F* will not drop too far out of the holder, I provide the tube *A*, a short distance above the ring *h*, with a sleeve or gripper, *I*, which fits loosely over said tube *A* 75 and slides within the contracted lower part of the tube *E*. The sleeve or gripper *I* has outwardly-extending lugs *j*, that pass through the enlargements *d* of the slits *b*. At its lower end the gripper *I* has a number of spring- 80 claws, *j*², which pass inward through slots *l* of the tube *A* to grasp the lead, Fig. 1.

There are as many lugs *j* as there are slits *b* and enlargements *d*, and as many claws *j*² as there are slots *l*, also as many bridges *i* on ring 85 *h* as there are slits *b* and enlargements *e*.

To set the lead and gripper to work, the gripper is first slid up on the tube *A* until the claws *j*² pass out of and above the slots *l*, when the tube *A* is clear on the inside and the lead 90 *B* may be dropped into the tube *A* from above until it is stopped by the closed jaws *F*. The gripper *I* is then slipped down along the tube *A* until the spring-claws *j*² pass through the slits *l* and grip the lead *B* securely. The lugs 95 *j* are now near the upper ends of the slots *d*. By pressing down on the tube *A* the claws *F* will now be opened by the ring *h*, as before stated, and the lead will slide down, carrying the gripper *I* with it, until the gripper is arrested by the lugs *j* striking the lower ends of the slots *d*. By now releasing the pressure on 100

tube A, the claws F will act to hold the lead firmly in place. (See dotted lines, Fig. 2.) To return the lead within the pencil, it is only necessary to invert the pencil and press upon 5 the tube A, when the claws F will open and allow the lead to slide inward until the lugs j strike the upper ends of the slots d.

The upper end of tube A, where it projects above the sheath D, is surrounded by a sleeve, 10 J, secured to the sheath D. L is a cap piece covering the upper end of the tube A, and held in place by friction or otherwise to prevent the lead from slipping out of the pencil at that end.

15 It is not necessary to reset the gripper I every time the pencil is used, but only when the point is too short for use.

If desired, the lead can be inserted in the pencil at the writing end by opening the claws 20 F and slipping the gripper I back on tube A until the claws j² are out of the slots l, which leaves a clear passage for the entry of the lead. The gripper I can then be let down to engage the lead, as before described.

25 In the modification shown in Fig. 7 the tube A, instead of passing through the sheath D, has an enlarged part, m, above the shoulder g and surrounds the sheath and is secured thereto. The tube E, instead of being secured 30 to the sheath D, is fitted loosely over same and over the part m of tube A. The upper end of the tube E is turned inward, forming a flange, n, which flange prevents its slipping off the sheath D downwardly. With this construction I am enabled to make a double-end 35 pencil, if desired.

In Fig. 8 the spring f is arranged at the upper end of the pencil and bears at one end against the end of sheath D and at the 40 other end against a ring or flange, p, on the inner end of cap-piece L. The cap L is provided with one or more slots, q, which receive pins r from the tube A, to limit the movement of the cap-piece L on tube A.

45 The sleeve J has an inwardly-projecting flange, s, which limits the upward movement of cap L. Part of tube A is surrounded by a sliding tube, M, which is preferably of heavy material to give it weight. At the lower end 50 the tube M is provided with slots t, to receive the lugs j on gripper I. Near the upper end of tube A are a number of outwardly-projecting springs, o, which are arranged to bear against the inner wall of the tube M, and 55 which also extend into the cap L. The tube M, I term a "sliding hammer," for convenience.

This pencil operates as follows: Suppose the parts are arranged as shown in Fig. 8—that 60 is, the gripper I pushed upward, so as to leave a clear passage in the tube A for the lead which is contained in the tube A, the sliding hammer M, held by the springs o in the upward position, and the cap L and tube A 65 pressed upward by the spring f—by turning

the pencil-point downward the lead slides outward until it is arrested by the closed claws F. Pressure is now brought to bear upon the cap L, and the same moved slightly without moving the tube A, owing to the slot q. A bevel, 70 u, on the inner side of cap L now strikes the springs o, compressing them, thereby releasing them from the "hammer" M. The hammer immediately drops on the lugs j and drives the gripper I down, when the claws j² pass into 75 the slots l and grip the lead. By this time the pin r has reached the upper end of the slot q, and by still continuing the pressure on cap L the tube A is now moved down and the ring h caused to open the jaws F, as before described. 80 The weight of the hammer M now carries the gripper I still farther down, and with it the lead, until the lugs j strike the shoulder w on tube E. The jaws F close on the lead as soon as the spring f is permitted to elevate the tube 85 A. To return the lead into the pencil, pressure is applied to cap L, while the pencil is held in an inverted position until the claws F open, when the hammer M will fall downward, carrying the gripper and lead with it. 90 The hammer will then pass over springs o, so as to be afterward held by them until said hammer is again to be used, in manner already described.

Having now described my invention, what I 95 claim is—

1. The tube A, having the perforated ring h, in combination with the jaws F, that pass through the perforations of said ring, substantially as herein shown and described. 100

2. The tube A, having perforated ring h and cross-pieces i therein, in combination with the tube E, having longitudinal slits b e, adapted to receive the cross-pieces i, and with the lead-holding jaws F, that pass through the 105 perforations of said ring, substantially as described.

3. The tube A, having slots l, in combination with gripper I, having claws j² and lugs j, and tube E, having longitudinal slits d, substantially as herein shown and described. 110

4. The tube A, having slots l and ring h, in combination with the gripper I, having claws j² and lugs j, and with the tube E, having longitudinal slots b d e, substantially as described. 115

5. The tube A, having springs o, in combination with the sliding hammer M and gripper I, substantially as described.

6. The tube A, having slots l, springs o, and 120 ring h, in combination with the sliding hammer M, having slots t, gripper I, having claws j² and lugs j, and cap L, adapted to compress the springs o to release the hammer M, as set forth.

THEO. O. L. SCHRADER.
